UNITED STATES PATENT OFFICE.

DAVID H. WATTS, JR., OF PHILADELPHIA, PENNSYLVANIA.

METALLIC WALL-CLOSET.

No. 809,592.

Specification of Letters Patent.

Patented Jan. 9, 1906.

Application filed December 7, 1904. Serial No. 235,864.

To all whom it may concern:

Be it known that I, DAVID H. WATTS, Jr., a citizen of the United States, residing in Philadelphia, Pennsylvania, have invented 5 certain Improvements in Metallic Wall-Closets, of which the following is a specification.

The object of my invention is to construct a closet as an article of manufacture which can be inserted in the partition between two 10 rooms.

My invention is useful particularly as a medicine-closet for a bath-room, it being desirable to make the closet entirely of metal and enamel the inside walls, so that it can be 15 readily cleansed when desired.

Referring to the accompanying drawings, Figure 1 is a perspective view of my improved closet. Fig. 2 is a front view showing the closet embedded in the wall, the studding being shown by dotted lines. Fig. 3 is a section on the line 3 3, Fig. 2. Fig. 4 is a section on the line 4 4, Fig. 2. Fig. 5 is an enlarged view showing a detail of the frame of the closet. Fig. 6 is an enlarged view showing 20 the method of pivoting the door. Fig. 7 is a detached perspective view of the body of the closet. Fig. 8 is a view of a modification, and Fig. 9 is a sectional view showing the preferred form of door.

25 The body A of the closet is made of a single casting and having its inner surface enamelled. This section has lugs a, to which is secured the angle-iron rim B. In the present instance screws b are used to secure the two 30 parts together.

The body of the closet A is so designed as to fit between the two plaster surfaces d d of the partition D, the section being mounted 35 between the vertical studding c c (shown by 40 dotted lines in Fig. 2) and the transverse studding-timbers c' and may be secured to the studding, if found necessary.

Secured to the angle-frame B is an angle-facing strip E, having a face e, which overlaps the plaster and makes a finish or frame 45 for the closet, while the section e' extends into the closet and is secured to the angle-frame B by a screw or other fastening e'.

F is the door, which is hung on concealed 50 pivots ff at one side and has a bolt or lock f' at the opposite side. A washer f² is mounted on the lower pivot-pin f between the door and the sill, so as to allow for the sag of the door due to its weight. The door may be 55 made either solid or in the form of a frame, as shown in the drawings, and in this frame is a

mirror F', which may be backed by a plate f³, of any suitable material, preferably enamelled sheet metal or white glass, as shown in Fig. 9.

60

On the sides of the body-section A are brackets a', which support the shelves i, preferably made of glass, although they may be made of metal or wood. In some instances I may make the shelves adjustable, 65 and, as shown in Fig. 6, I may perforate the body A with a series of holes i', into which can be inserted supporting-pins i² for the shelves i.

While I have shown lugs a on the body A, 70 a continuous flange may be substituted for the lugs when desired; but this is not necessary when the angle-frame B is used.

It will be seen that the above-described 75 closet can be readily mounted in an ordinary partition flush with the wall and being made entirely of metal can readily be kept clean, and it can be so mounted in the partition that the mirror will take the place of the ordinary bath-room mirror.

80

In mounting the closet in the partition the studding is so spaced that the body portion A will fit in the opening formed by the studding and the cross-pieces. The metallic frame B is first secured to the body portion 85 and then mounted in position. The plaster of the walls is then completed, securing the body of the closet permanently in the wall. After the wall is completely finished then the frame E is secured to the frame B by means 90 of the screws e², the door being hung to the frame E before the frame is secured in position.

I claim as my invention—

1. The combination in a closet, of a metallic body portion arranged to fit in the space between the two walls of a partition, and a frame secured to the open end of the body portion and overlapping one wall forming a finish, and a door hung to said frame, substantially as specified.

95

2. The combination of a body portion, lugs thereon, an angle-frame having one member secured to the lugs, the other member extending through one wall of the partition, a 105 facing-frame secured to the angle-frame, and a door hung to the facing-frame, substantially as specified.

100

3. The combination in a closet, of a body portion adapted to be mounted between the 110 walls of a partition, lugs on the body portion, a metallic angle-frame having one angle

secured to the body portion, the other angle extending through one wall of the partition and a metallic angle facing-strip overlapping the wall and secured to the angle-frame, substantially as specified.

4. The combination in a closet, of a body portion made of cast metal and enameled on the inside, shelf-supports secured to the body portion, shelves mounted thereon, a metallic angle-frame having one member secured to the body portion, the other member extending through one wall of the partition, an angle facing-frame having one member overlapping one of the members of the angle-frame and the other member overlapping the wall of the partition, and a door pivoted to the facing-frame, substantially as specified.

5. The combination in a closet, of a body portion, a frame secured to the body portion, a door, concealed pivots by which the door is hung to the frame, and a washer on the pivot between the lower portion of the door and the frame, substantially as specified.

6. The combination in a closet, of a parti-

tion, studding therein, a cast-metal body portion having lugs and having its inner surface enameled, a metallic angle-frame, screws fastening one member of the frame to the lugs of the body portion, the other member of the frame extending through the wall of the partition and flush with the outer surface thereof, an angle facing-frame, screws fastening one member of the said facing-frame to the angle-frame, the other member of the facing-frame overlapping the wall of the partition, a door mounted in the facing-frame, concealed pivots by which the door is hung to the frame, said door being made in the form of a frame, a glass mounted in the frame, and a backing for the glass also mounted in the frame, substantially as specified.

In testimony whereof I have signed my name to this specification in the presence of two subscribing witnesses.

DAVID H. WATTS, JR.
